[57] CLAIM

The ornamental design for a combined sewing machine

and work support extension, substantially as shown and described.

DESCRIPTION

FIG. 1 is a front perspective view of a combined sewing machine and work support extension showing our new design with the work support extension removed for convenience of illustration;

FIG. 2 is a front perspective view of the work support extension, the sewing machine having been removed for convenience of illustration;

FIG. 3 is a top plan view of the combined sewing machine and work support extension;

FIG. 4 is a front elevational view thereof;

FIG. 5 is a rear elevational view thereof;

FIG. 6 is a bottom view thereof;

FIG. 7 is a left end elevational view thereof;

FIG. 8 is a right end elevational view thereof;

FIG. 9 is similar to FIG. 3 with the work support extension removed;

FIG. 10 is similar to FIG. 4 with the work support extension removed;

FIG. 11 is similar to FIG. 5 with the work support extension removed;

FIG. 12 is similar to FIG. 6 with the work support extension removed;

FIG. 13 is similar to FIG. 7 with the work support extension removed;

FIG. 14 is similar to FIG. 8 with the work support extension removed;

FIG. 15 is a top plan view of the work supporting extension apart from the sewing machine;

FIG. 16 is a left end view of the work supporting extension apart from the sewing machine;

FIG. 17 is a right end view of the work support extension apart from the sewing machine;

FIG. 18 is a front elevational view of the work support extension apart from the sewing machine;

FIG. 19 is a bottom plan view of the work support extension apart from the sewing machine; and

FIG. 20 is a rear elevational view of the work support extension apart from the sewing machine.
